United States Patent Office

Des. 211,465
Patented June 18, 1968

211,465

SOFA OR THE LIKE

Warren Platner, North Haven, Conn., assignor to Knoll
Associates, Inc., New York, N.Y., a corporation of New York

Original design application Aug. 31, 1965, Ser. No.
86,788. Divided and this application Sept. 11, 1967,
Ser. No. 9,147

Term of patent 14 years.

(Cl. D15—11)

Fig. 1.

Fig. 2.

FIG. 1 is a front perspective view of a sofa embodying the new design.

FIG. 2 is a side perspective view of the sofa of FIG. 1.

FIG. 3 is a rear perspective view of the sofa of FIG. 1.

The side of the article not shown is a mirror image of the side shown.

This application is a division of my copending application Ser. No. D. 86,788, filed Aug. 31, 1965, for an Article of Furniture.

I claim:

The ornamental design for a sofa or the like, as shown and described.
